US00D622745S

(12) **United States Design Patent**
Pearce et al.

(10) **Patent No.:** US D622,745 S
(45) **Date of Patent:** ** *Aug. 31, 2010

(54) **DRILL BIT WITH TAPERED WATERWAY**

(75) Inventors: **Cody A. Pearce**, Midvale, UT (US);
Michael D. Rupp, Murray, UT (US);
Christian M. Lambert, Draper, UT
(US)

(73) Assignee: **Longyear TM, Inc.**, South Jordan, UT
(US)

(**) Term: **14 Years**

(21) Appl. No.: **29/354,579**

(22) Filed: **Jan. 26, 2010**

(57) **CLAIM**

The ornamental design for a drill bit with tapered waterway, as shown and described.

DESCRIPTION

FIG. 1 is a perspective view of a drill bit with tapered waterway;

FIG. 2 is another perspective view of the drill bit with tapered waterway shown in FIG. 1;

FIG. 3 is a top plan view of the drill bit with tapered waterway shown in FIG. 1;

FIG. 4 is rear elevational view of the drill bit with tapered waterway shown in FIG. 1;

FIG. 5 is a front elevational view of the drill bit with tapered waterway shown in FIG. 1;

FIG. 6 is a bottom plan view of the drill bit with tapered waterway shown in FIG. 1;

FIG. 7 is a left side elevational view of the drill bit with tapered waterway shown in FIG. 1; and,

FIG. 8 is a right side elevational view of the drill bit with tapered waterway shown in FIG. 1.
